UNITED STATES PATENT OFFICE.

FRANK T. SCHLOTZHAUER, OF SAN FRANCISCO, CALIFORNIA.

OIL AND GAS BURNER.

Application filed July 6, 1921. Serial No. 482,681.

To all whom it may concern:

Be it known that I, FRANK T. SCHLOTZHAUER, a citizen of the United States, and a resident of the city and county of San Francisco, State of California, have invented a certain new and useful Oil and Gas Burner, of which the following is a specification.

This invention relates to a heating apparatus of the character in which liquid fuel is generated into a gas which is mixed with air and consumed at a burner.

As is well known, a highly efficient heat producing apparatus comprises a so called "retort" or generator usually in the form of a comparatively small tube into which liquid fuel is introduced at one end and, the tube being subjected to heat, the oil is vaporized and gasified and passes out of the tube into a mixing chamber where it is commingled with the desired proportion of air when it is ready to be burned at a suitable burner device. Such a burner device of a well known and practical form consists of a burner chamber provided with a plurality of apertures or throats in a plane and in these throats are arranged lava or other heat resisting elements, perforated or otherwise designed to permit the escape of the combustible gas from the burner chamber in a myriad of small jets which generally burn with a blue flame of great heat.

It is one of the objects of the present invention to provide an improvement in oil burners having retorts for generating the fuel from a liquid to a gaseous form. More particularly, it is an object of my invention to provide an improved generating tube or retort in the form of a spiral coil.

Fig. 1 is a vertical section of a form of burner erected as a portable heater having a retort embodying my invention.

Fig. 2 is a plan view of the retort pipe.

Fig. 3 is a plan of the retort heating burner and the fragment of the circular burner chamber and

Fig. 4 is a section on line 4—4 of Fig. 3.

A very convenient and useful form of a stove of the character indicated is shown in Fig. 1, in which the burner chamber 2^c, is shown as of circular form in plan and is provided on its top with a circular series of mantles 8^c, which surround a fire resistant backing in the form of a chamber C, having an open top in which may be inserted any removable vessel as a container V, which, when inserted in the circular refractory

backing C, will become heated and thus may be utilized for the heating of water or other material that may be placed in the vessel V. In this type of burner, it may be desirable to provide the stove with an oil tank T, arranged below the burner and supported suitably upon the leg or frame structure.

A gas generating tube or retort embodying my invention is shown in Fig. 2, in which the tube is arranged in the form of a spiral 11^b, the coils of which lie in a common plane with the inlet and outlet ends of the coil being arranged at the outer extremity and the central portion of the spiral. To efficiently heat this form of retort coil, a form of burner is shown as in the form of a hollow disc 25, Figs. 3 and 4, having in its top a series of gas outlet apertures 26; the central portion of the top being provided with a pad 7^c of asbestos, as at 27, which when saturated with alcohol and the latter is ignited, will serve for initially heating the superposed coil 11^b, as shown in Fig. 1.

The outlet from the coil leads into the mixing chamber 12^c, thence into the annular burner chamber 2^c. After the initial heating of the coil and gas is generated, some of the gas is taken from the chamber 2^c, by a short connection 28, leading to the burner 25, and the gas escaping at the outlets 26, maintains the generating coil 11^b in heated condition, as required.

While any suitable provision may be utilized for igniting the fuel at the burner 25, this may be conveniently accomplished by the insertion of an alcohol discharging nozzle indicated in dotted lines N, which may be passed through a recess 2^b, in the top of the burner 2^c.

It is manifest that the spiral coil 11^b, will quickly generate gas from the oil by reason of the compact relation of the coils of the tube, which also provides a very considerable length of tubing in a comparatively small area. An advantage of the spiral form over a straight retort is that the whole length of the spiral coil is heated by a comparatively small zone of combustion as distinguished from a straight retort pipe of a given length, only a portion of which, considerably less than its length, is heated.

What is claimed is:

1. In an oil burning heater, an annular body providing a fuel chamber of annular form, a plurality of burners communicating with the chamber, and means for heating oil

- to be used in the burner comprising a flat convoluted pipe disposed within the space encompassed by the body.
2. In an oil burning heater, an annular body providing a fuel chamber of annular form, a plurality of burners communicating with the chamber, a flat, convoluted pipe disposed within the space encompassed by the body, for heating oil to be used in the burner, and an auxiliary heater located in proximity to the coil.
3. In an oil burning heater, an annular body providing a fuel chamber of annular form, a plurality of burners communicating with the chamber, a flat, convoluted pipe disposed within the space encompassed by the body, for heating oil to be used in the burner, and an auxiliary heater below the coiled pipe having fuel openings disposed only near the outer turns of the coiled pipe.
4. In an oil burning heater, an annular body providing a fuel chamber of annular form, a plurality of burners communicating with the chamber, a flat convoluted pipe disposed within the space encompassed by the body, for heating oil to be used in the burner, and an auxiliary heater for the pipe dis-
- posed below it and connected to the main chamber.
5. In an oil burner, an annular body forming an annular fuel chamber, a plurality of burners communicating with the chamber, refractory mantles disposed over the burners and forming, with the annular body, an interior space, and a flat convoluted pipe for heating oil to be used in the burner, disposed within this space.
6. In an oil burning stove an annular gaseous fuel chamber, a retort arranged within the circular chamber and surrounded thereby and which chamber is connected to the discharge end of the retort, a preliminary igniting device including a pan arranged below the retort to receive an initial charge of combustible material for initially heating the retort, and a gas connection between the said chamber and the said device for supplying a portion of the generated fuel to the igniting device after generation has started in the retort.

In testimony whereof, I have hereunto set my hand.

FRANK T. SCHLOTZHAUER.
